UNITED STATES PATENT OFFICE.

GEORGE HUGHES, OF WASHINGTON, DISTRICT OF COLUMBIA.

GRINDING AND MIXING MILL.

SPECIFICATION forming part of Letters Patent No. 394,771, dated December 18, 1888.

Application filed June 22, 1888. Serial No. 277,862. (No model.)

To all whom it may concern:

Be it known that I, GEORGE HUGHES, of the city of Washington, in the District of Columbia, have invented certain new and useful Improvements in Grinding and Mixing Mills, of which the following is a specification, reference being had to the accompanying drawings, and to the letters of reference marked thereon.

- 10 The object of my invention is to provide a mill that can be easily adjusted to grind and mix materials of different degrees of fineness, and particularly adapted for preparing mortar and concrete. It may, however, be used 15 for grinding and mixing paint or the like. By its use I propose to utilize material which has heretofore been comparatively worthless—such as soft-stone chippings—as a substitute for or addition to sand in mixing mortar. 20 Ashes can also be advantageously used for the same purpose. Furthermore, the material for concrete—such as brick, stone, &c.—can be broken into suitable size and discharged directly to be mixed with the lime and cement. 25 My invention consists in the several details of construction and arrangement hereinafter fully set forth.

In the accompanying drawings, Figure 1 is a front elevation, partly broken away, of a mill 30 embodying my improvements. Fig. 2 is a vertical section through the line $x-x$ of Fig. 1. Fig. 3 is a side view. Fig. 4 is a horizontal section, and Fig. 5 a detail.

Similar letters of reference represent similar parts in the respective figures.

A is the bed or foundation of the machine, which may be of heavy timber, masonry, or other construction.

B B represent the main housing or posts of the mill, made, preferably, of cast-iron and of suitable strength, and B' B' are braces.

C is a cross-beam or casting, which ties the two posts B B together. The table or revolving bed upon which the materials are ground 45 is represented by D, it being provided with a central shaft, a, which has its upper bearing in the cross-beam C. The upper end of the shaft a projects above the beam C and is screw-threaded for the reception of the nut a', 50 for the purpose of partially supporting the

weight of the table and its contents and lessening the friction upon the driving-shaft. The table or bed D is made of cast-iron, and with a wall, d, around its periphery of suitable depth. The wall is made inwardly slanting, as shown in the drawings, for a purpose hereinafter specified. I prefer to provide the table or bed with a false bottom, d', of cast-iron, made in two sections, so as to be readily inserted and to fit around the central shaft, a. 55 The periphery of the table is provided with hinged portions d'', the bottoms of which are flush with the top of the false bottom, and which, when let down, as shown in Fig. 2, allow the contents of the table to be discharged.

The posts B B are each provided with a slot, b, in which rests a squared end of the axle E, whereon are mounted the grinding or pulverizing rolls E'. These rolls are of cast-iron and hollow, being filled with concrete or other material to give them the requisite weight. The axle is perforated centrally for the reception of the shaft a, the axle serving to a certain extent as a lower bearing for the 75 shaft. At the lower end of the shaft a, or where it unites with the table, is placed a scraper, consisting, preferably, of two separate wings, F, as shown in Fig. 4. The scraper may, however, be differently arranged, provided it shall rest in close proximity to the table. The wings F are each supported by an upright post, c, secured to the axle and partake of the vertical movement of which the rolls are capable. The under side of the 80 table D is provided with teeth d'', which engage with a pinion, G, mounted upon the shaft e, carried by the posts B, and having a driving-pulley, f. Upon the shaft e is mounted a loose wheel, H, which serves as a support to 90 the table or bed, equalizes the strain upon the gearing, and prevents the binding thereof which would occur were the table not maintained in a horizontal position. The table is strengthened on its under side by suitable 95 ribs.

G, G', G², and G³ are shafts having their ends squared and supported in suitable housings on the posts B, those supporting the shafts G² G³ permitting them to be adjusted 100

both vertically and laterally, for a purpose hereinafter specified. The shafts carry the corrugated rollers g g , $g' g'$, $g^2 g^2$, and $g^3 g^3$, which revolve on them. These rollers are arranged in pairs, as shown, those carried by the shafts $G^2 G^3$ being nearer to each other than those on the shafts $G G'$, in order that they may still further reduce the material which passes between them from the upper rollers. The rollers of each pair of shafts are given the necessary reverse movement with respect to their fellows by means of the cross-belts g^4 , which pass over pulleys integral with or rigidly connected to the rollers. Motion is imparted to the upper corrugated rollers by means of the belts $H' H'$, which pass around the pulleys $h h$, mounted on the driving-shaft e , and also around the pulleys $h' h'$ of the rollers on either of the upper shafts. The lower set of corrugated rollers are revolved by means of the gear-wheels I , rigidly connected to the outer faces of the pulverizing-rolls E' , and which engage the gear-wheels I' , rigidly attached to two of the rollers, one on each shaft and diagonal to each other.

While I have illustrated and described a system of belts and pulleys to operate the corrugated rollers, it is obvious that sprocket-wheels and chains may sometimes be advantageously substituted without departing from the spirit of my invention.

$J J$ are hoppers supported by the hangers j , attached to the cross-beam C and arranged immediately over the corrugated rollers.

$K K$ are belts provided with buckets k and running over the pulleys k' and k^2 , mounted in suitable bearings supported, respectively, by the cross-beam C and the lower part of the frame. These carrier-belts are for the purpose of elevating the material to be crushed from the lower hoppers, L , to the hoppers J , whence it is fed to the corrugated rollers. The carrier-belts are driven by belts running from the driving-shaft e to the pulleys k^2 .

$M M$ are screens supported in any suitable manner by the frame and for the purpose of preventing the crushed material falling outside the table D after it leaves the lower corrugated rollers.

L is a scraper attached to the vertical rod l , which slides in bearings in the axle E and cross-beam C . The upper end of the rod l is connected to the pivoted lever l' , operated by means of the chain l'' . While the material is being pulverized on the table, the scraper L is held in the position shown in Fig. 1. When, however, it is desired to discharge the material from the table, the chain l'' is released from the catch l' , and the scraper will fall by its gravity to the position shown in Fig. 3. The hinged portions d^2 will be let down, and as the table continues to revolve the material will be banked up against the scraper L and discharged through the openings in the periphery of the table.

In operation, when it is required to grind and mix mortar, the rollers E' rest on the bed of the table D , and if soft stone is to be used as a substitute for or addition to the sand it is carried up by the carrier-belts K to the hoppers J and crushed between the corrugated rollers, the upper rollers being arranged about two inches apart and the lower ones about one inch apart. It then falls onto the table D , and will be pulverized and thoroughly mixed with the lime by means of the rollers E' , the scrapers F serving to constantly turn the mass over and force it under the rollers E' as the table is revolved. When thoroughly mixed, the scraper L is lowered and the hinged portions d^2 are let down, when, the table constantly revolving, the mass will be banked up against the scraper L and discharged, as hereinbefore stated.

The operation is the same in grinding and mixing paint.

When the mill is to be used for preparing concrete, the axle E is elevated by means of the levers x , and blocks y are inserted under the ends in the slots b , as shown in Fig. 5, to support it and keep the rollers E' at the necessary height—say one and a half or two inches above the bottom of the table. The lower corrugated rollers must also be elevated to the same extent and supported in a similar manner. The upper rollers need not be moved, as they are sufficiently above the lower ones to allow of this vertical adjustment. The lower corrugated rollers can also be adjusted laterally, so as to have a space of one and a half to two inches between them, according to the predetermined size of the pieces of brick and stone for the concrete. The said rollers are held in such position by means of blocks y' , the set-screws y^2 serving to hold them steady in whatever position they are vertically adjusted. The operation will then be similar to that already described for mixing mortar.

Having described my invention, I claim—

1. The combination, with the revolving bed or table, of the vertically-adjustable rolls traveling thereon, and the upper and lower pairs of corrugated rollers arranged above the rolls, the lower pairs of said rollers being vertically and laterally adjustable, substantially as set forth.

2. In a mill, the combination, with the revolving table, the rolls traveling thereon, and the corrugated rollers arranged above said rolls, of screens supported by the frame of the mill to prevent material after passing between the rollers from falling outside the table, substantially as specified.

3. In a mill, the combination, with the main housings or posts $B B$ and the cross-beam C , of a driving-shaft, e , carried by the posts $B B$, a loose wheel, H , and a toothed pinion, G , mounted on said shaft, and a revolving table provided with a central supporting-

shaft which passes through the cross-beam C and is screw-threaded for the reception of a nut which rests on said cross-beam, the said table being provided with teeth on its under side, which engage with the pinion G and the loose wheel H, serving to keep the table in a horizontal position, substantially as specified.

In testimony whereof I have hereunto set my hand and seal.

GEORGE HUGHES. [L. S.]
